UNITED STATES PATENT OFFICE.

THDOR BABICH, OF EAGLE RIVER, WISCONSIN.

GATE,

Application filed October 6, 1923. Serial No. 666,969.

To all whom it may concern:

Be it known that I, THDOR BABICH, a citizen of the United States, residing at Eagle River, in the county of Vilas and 5 State of Wisconsin, have invented new and useful Improvements in Gates, of which the following is a specification.

This invention relates to a gate, the general object of the invention being to provide means for causing the wheels of the vehicle to open the gate, as the vehicle approaches the same and to provide means for closing the gate after the vehicle has passed through the same.

15 This invention also consists in certain other features of construction and in the combination and arrangement of the several parts, to be hereinafter fully described, illustrated in the accompanying drawings
20 and specifically pointed out in the appended claims.

In describing my invention in detail, reference will be had to the accompanying drawings wherein like characters denote like or corresponding parts throughout the several views, and in which:

Fig. 1 is a plan view showing a portion of a fence and my improved gate.

Fig. 2 is a side view showing the gate in closed position.

Fig. 3 is a sectional view on line 3-3 of Fig. 2.

Figs. 4 and 5 are detail perspective views of the opposed ends of the tracks.

35 Fig. 6 is a sectional view on line 6—6 of Fig. 2.
Fig. 7 is a detail sectional view of the opposed ends of the tilttable platforms showing the bell crank arm in operable position
40 therewith.

Fig. 8 is a perspective view of one of the bell crank arms.

In these views 1 indicates portions of the fence on each side of the gate opening and 2 indicates the gate sections which are slidably mounted on the supporting posts 3 by means of the tracks 4 and the rollers 5. A curved arm 6 engages a bracket 7 on each section and this arm is pivotally mounted at its lower end to one of the posts as shown at 8. Each arm has connected therewith a pinion 9 which engages the teeth of a segmental gear 10 which is also pivoted to one of the posts and which has an arm 11 thereon which is attached to a bell crank 12. A weight 13 is attached to the upper end of

each bell crank by means of the cable 14 which passes over a guiding pulley 15 which is attached to an arm 16 on a supporting post. This weight tends to hold the bell crank in raised position with the curved arm 6 in upright position so as to hold the gate closed. A pair of tiltable platforms 17 are arranged adjacent the outer edges of the roadway so that they will be engaged by the wheels of the vehicle and depressed. These platforms are attached to the bell cranks in such a manner that when they are depressed the bell cranks will be forced downwardly so as to rock the gears 10 and thus throw the curved arms outwardly by means of the pinions so that the gate sections will be moved to open position. The platforms are made long enough to hold the gate in open position until the vehicle has passed through and then when the platforms are released by the vehicle the weights will return the parts to normal position and thus the gate will be closed. Latch means 18 may be placed on the abutting parts of the gate sections if desired so as to prevent the sections from having lateral play.

From the foregoing it will be seen that the gate will be opened by the wheels of the vehicle striking the platforms so that it is not necessary for an occupant of the vehicle to get out to open the gate. The gate will automatically close as soon as the vehicle passes through and the gate will be opened by a vehicle coming in either direction. 90

It is thought from the foregoing description that the advantages and novel features of my invention will be readily apparent.

I desire it to be understood that I may make changes in the construction and in the combination and arrangement of the several parts, provided that such changes fall within the scope of the appended claims. 95

What I claim is:

1. The combination with a pair of slide-
able gate sections, of rocking members con-
nected to the gate sections, manipulating
arms connected to the rocking members,
pairs of tiltable platforms adjacent the
manipulating arms of the rocking members,
bell cranks carried between the opposed ends
of the tiltable platforms, and elevating
means connected to the bell cranks.

2. The combination with a pair of slide- 110
able gate sections, of rocking members connected at their free ends with the gate sec-

tions and having their inner ends serrated, manipulating arms pivoted below the rocking members in mesh with the serrations of the inner ends of the rocking members and 5 having their free ends extended approximately at right angles thereto, tiltable platforms disposed at right angles to the free ends of the rocking member manipulating arms and having their opposed ends

grooved, crank arms slidably seated in the 10 grooves of the tiltable platforms, pivotal means connecting the crank arms to the manipulating arms, and elevating means connected to the free ends of the crank arms. 15

In testimony whereof I affix my signature.

THDOR BABICH.
